FRANK H. SKINNER, OF CHICAGO, ILLINOIS.

DENTAL INSTRUMENT.

1,071,106.

Specification of Letters Patent. Patented Aug. 26, 1913.

Application filed May 5, 1911. Serial No. 625,390.

To all whom it may concern:

Be it known that I, FRANK H. SKINNER, a citizen of the United States, residing in the city of Chicago, county of Cook, and 5 State of Illinois, have invented certain new and useful Improvements in Dental Instruments, of which the following is a specification.

This invention relates to instruments used 10 in dental surgery and has particular reference to a device for removing the crown of a tooth.

The object of the invention is to provide an efficient and convenient instrument particularly adapted for this purpose, and one which will facilitate the speedy removal of a crown without subjecting the patient to pain or inconvenience, or without straining the tissues, membranes and nerves of the 20 tooth operated upon.

With the above-named objects in view my invention consists in the novel instrument hereinafter described in detail, illustrated in the accompanying drawing and particularly 25 described in the appended claim.

In the drawing—Figure 1 is a top plan view of substantially a full-sized instrument embodying my invention, together with a portion of a lower jaw with the second molar of which the instrument is shown engaged. Fig. 2 is a side view of the instrument in the same working position, both upper and lower jaws being shown in vertical section. Figs. 3 and 4 are similar 30 views showing the instrument in different positions. Fig. 5 is a plan view of a double or reversible instrument. Fig. 6 is a side or edge view of same.

In Figs. 1 to 4, inclusive, 2 and 3 represent 40 a pair of jaw-bodies pivoted together on a pivot 4 through a compass-joint comprising a pair of disks 5 and 6 on the jaw 3 and a single disk on the jaw 2 held between the disks 5 and 6. In the jaw 3 is an elongated 45 or oblong transverse hole 8 through which passes a jaw-operating screw 9 that has threaded engagement at 10 with a threaded bore in the jaw 2. The screw 9 is provided with a thumb-piece 11 with the aid of which 50 the screw may be conveniently manipulated to draw the jaws together upon or release them from the work. On the screw is a collar 12 which bears against the jaw 3 and co-operates with the threads to move the 55 jaws.

The bodies of the jaws, without the beaks,

or the parts designated by the numerals 2 and 3, are substantially identical with the body portions of hand-vise jaws. In the present invention these bodies 2 and 3 are 60 extended by noses or beaks which project at angles from the body portions, so that the instrument, as a whole, minus the tips, is of elbow, form. Each nose or beak is also of elbow form, the bends being in opposite 65 directions and outwardly relative to the body of the tool or instrument. These elbows, noses, beaks or extensions are labeled 13 and 14, and on their tips, projecting toward each other, are wedges 15 and 16. As 70 shown in Figs. 1 to 4 each nose, beak, or elbow 13 or 14 is, as to the body portion, first an outward bend, then an inward and downward bend, and is provided with the inwardly or horizontally projecting wedge. 75 This formation of each jaw forms a roomy space between the noses or beaks adapted to receive the top or crown of a tooth while the wedges are operating at the base of the crown. That is the noses or beaks straddle 80 the tooth even when the wedge-edges are brought together under the base of the crown or between the crown and the root of a tooth. On the other hand, the elevation of the jaw-bodies above the working positions of the beaks shown in Figs. 1 to 4 and their inclination relative to the beaks places the body of the instrument substantially in line with the row of teeth, particularly the upper row, when said body is alined between the upper and lower row of teeth, or 85 between them lengthwise. The elevation and inclination of the jaw-body also affords the operator an unobstructed view of the tooth operated upon when viewed from the rear or front of the instrument and the straddle of the beaks, or space between them, 90 affords an unobstructed view from above.

17 represents, in Figs. 1 to 4 the lower jaw of a patient, 18 designates the root of 100 a tooth crowned with a crown 19 cemented to a post or crown pin 20 secured or cemented to the root of the tooth.

21 represents the plane or line of junction between the crown and the root at 105 which are shown placed the edges of the wedges 15 and 16 ready to be forced toward each other to crowd the artificial crown and natural root of a tooth apart. In Fig. 4 the crown is shown partly removed, or loosened 110 from the root or post, after having turned the operating screw to draw the jaws

toward each other. This operation of the instrument need not be appreciably felt by the patient, because the lateral strains are balanced by the opposition of the wedges, and longitudinally of the axis of the tooth the strains are likewise balanced by the action and reaction against the top of the root and bottom of the crown, respectively, divided to opposite sides of the crown pin or axis of the tooth.

10 In removing a crown from one of the innermost, or third, molars the instrument may be operated without stretching the corner of the mouth or straining the cheek, as 15 the angle of the body of the instrument relative to the beaks permits placing the instrument in line with the upper row of teeth and substantially parallel with the tops of their crowns, and, as shown in Fig. 2, there 20 is also room for operation of the thumb-piece of the screw when said piece is directed inwardly. In the modified form or double instrument shown in Figs. 5 and 6 any tooth may be operated upon with the 25 thumb-piece always outside of the mouth, as will appear more fully in connection with the description of the double instrument.

30 In order to make it possible to place the thumb-piece of the screw in the same relative position whether it be an upper or lower, right or left tooth, I have provided the double form shown in Figs. 5 and 6. In this form by shifting the screw the thumb-piece may always extend outwardly. 35 The double instrument is composed of just as few members, pieces or stampings as the

first-described instrument. In the double form the jaws and beaks extend in duplicate to both sides of the pivot in opposite directions, and these jaw-bodies are labeled 22 40 and 23. The joint is substantially the same as that shown in Fig. 1, with the modification that the joint-disks 5, 6 and 7 carry two instead of only one pair of jaws. In the double construction the holes for the 45 operating screw are duplicated, so that when the right-hand end of the instrument, as it appears in, say, Fig. 5, is used the screw is simply removed from the left-hand end where it is shown in full lines and inserted 50 in the dotted line position shown to the right.

I claim as my invention—

In a dental instrument the combination with a pair of jaw-bodies pivoted together 55 intermediate of their ends, of pairs of elbows on the ends of said jaw-bodies, each said pair having coöperating beaks thereon, each said pair of elbows extending from said jaw-bodies oppositely to the angle of 60 extension of the other elbows, and means for applying mechanical force to either of said pairs of elbows with the aid of a single screw.

In testimony whereof I have hereunto set 65 my hand in the presence of two subscribing witnesses.

FRANK H. SKINNER.
